US0D1071953S

(12) **United States Design Patent** (10) **Patent No.:** **US D1,071,953 S**
Raslambekov (45) **Date of Patent:** **** Apr. 22, 2025**

(54) **DISPLAY SCREEN OR PORTION THEREOF WITH GRAPHICAL USER INTERFACE**

6,398,548 B1 6/2002 Muhammad et al.
6,463,344 B1 10/2002 Pavloskaia et al.
6,471,511 B1 10/2002 Chishti et al.
6,554,611 B2 4/2003 Chishti et al.

(71) Applicant: **ARKIMOS LTD.**, Larnaca (CY)

(Continued)

(72) Inventor: **Islam Khasanovich Raslambekov**,
Long Island City, NY (US)

FOREIGN PATENT DOCUMENTS

(73) Assignee: **ARKIMOS Ltd**, Larnaca (CY)

CN 102415916 A 4/2012
EM 008455869-0001 * 3/2021

(**) Term: **15 Years**

(Continued)

(21) Appl. No.: **29/846,587**

(22) Filed: **Jul. 18, 2022**

Related U.S. Application Data

(62) Division of application No. 29/749,667, filed on Sep. 8, 2020, now Pat. No. Des. 958,170.

Yijin "Optimum force magnitude for orthodontic tooth movement: A mathematic model", Am J Orthod Dentofacial Orthop. Jan. 1, 2004; vol. 125(1):71-7. doi: 10.1016/j.ajodo.2003.02.005.

USPC **D14/486**; D14/495

CLAIM

(58) **Field of Classification Search**

The ornamental design for a display screen or portion thereof with graphical user interface as shown and described.

USPC ..... D14/485—495

DESCRIPTION

CPC .. A61B 5/02; A61B 8/46; G06F 19/34; G06F 19/3418; G06F 19/3406; G06T 2207/30004; A61C 7/002; A61C 13/0004; A61C 9/0053; A61C 9/004

FIG. 1 is a front view of a 1st embodiment of a display screen or portion thereof with a graphical user interface according to my design; and,

See application file for complete search history.

FIG. 2 is a front view of a 2nd embodiment of the display screen or portion thereof with the graphical user interface according to my design.

(56) **References Cited**

The outermost large broken line rectangle, and all broken lines outside that rectangle, show a display screen and portions of a device, and form no part of the claimed design. All broken lines within the display screen showing the graphical user interface form no part of the claimed design.
